TOBACCO ARRANGING MACHINE

Stanley Hathaway, Greenville, N. C.

Application February 25, 1946, Serial No. 649,879

12 Claims. (Cl. 198—33)

1

This invention relates to article handling, and more particularly to the handling of plant leaves employed in manufacturing a product, one example being the handling of leaves of the tobacco plant in the manufacture of tobacco products.

This application is a continuation-in-part of my co-pending application Serial No. 579,653, filed February 24, 1945, and now abandoned, the subject matter of which is included with additions herein.

Tobacco leaves are harvested, then cured, and in some localities they are graded and tied in bundles, while in other localities as, for example, in the southeastern part of the United States, the leaves are not tied in bundles, but are left loose in disorderly piles. These loose tobacco leaves are known in the trade as "Georgia" tobacco, and are less desirable due to the possibilities of damage and loss, on account of the fact that they present problems in handling by automatic machinery.

Before this loose tobacco can be economically used in the manufacture of numerous tobacco products, the leaves must be arranged in an orderly fashion so that they can be handled by automatic machines, and it has been necessary heretofore to straighten or arrange the leaves by hand. This has amounted to slow, tedious, and consequently expensive procedure.

In addition to the handling of "Georgia" tobacco, or tobacco leaves which have not been tied and graded, and which require arranging or straightening, frequently the leaves of the tobacco which have been tied and bundled become untied, and disarranged, and it is desirable that these leaves likewise be subjected to the same process of straightening and arranging, so that they can be handled by the automatic machines.

It is an object of the invention to overcome the above problems of handling tobacco leaves, and the like, by providing a machine for straightening or arranging the leaves in a manner that they may be easily utilized in the manufacture of the desired tobacco or other products.

A further object of the invention is to provide a machine capable of receiving tobacco, or other leaves, in any quantity, and in any degree of disorder, and discharge them from the machine arranged in a straight or an orderly manner.

Another object of the invention is to provide a compact machine of few, simple, and inexpensive parts, so that the entire machine may be located on a single floor of a building.

Further objects and advantages of the inven-

2

tion will be apparent from the following description taken in conjunction with the drawings, wherein:

Figure 1 is a diagrammatic view, partially in cross-section, illustrating one application of the invention;

Fig. 2, a top plan view;

Fig. 3, a detailed view of the doffer; and

Fig. 4, a detailed view of the channel box.

10 The present invention is an improvement over machines merely for cutting or shredding leaves which are dropped, and is also an improvement over machines constructed merely to pick up by suction and convey dropped or loose leaves to other locations.

15 Briefly stated, the present invention comprises an upright chamber with suction producing means connected to its upper end, and also with an inlet adjacent its upper end for the introduction of leaves into the chamber so that they may float gently downward, and due to their heavier stems be discharged, stems first, from the bottom of the chamber. An inclined conveyor is employed for elevating and feeding the leaves into the upper end of the chamber, and a conveyor is disposed beneath the lower end of the chamber, and is provided with parallel channel forming members so that the leaves will be carried in parallel relation along said channels and discharged.

20 With further reference to the drawing, a leaf treating chamber 10, preferably rectangular in cross-section, having reduced upper and lower ends and of substantial height, is provided with an inlet 11, for receiving tobacco or other leaves 12, from a chute or inclined surface, 13.

25 The chamber 10 is designed to permit the leaves to fall downwardly therein, and accordingly is of substantial height, at least several times the length of the leaves to be treated, so that the leaves may have the opportunity of turning over and reversing ends during their downward movement in the chamber. The inlet 11, accordingly, is located near the upper end of the chamber 10,

30 and in order that the apparatus may be located on a single floor of a building, a conveyor 14 is employed for carrying leaves from a lower position, convenient to an operator, upwardly to the chute from which the leaves are fed into the chamber.

35 The conveyor 14 may be of any desired character, but preferably is an endless conveyor, as shown, having transverse ribs or cleats 15 to insure that the tobacco leaves will be carried upwardly by the conveyor. The lower end of the

conveyor extends around a pulley 16 mounted on supports 17, and the upper end of the conveyor extends around a pulley 18 on supports or frame 19. In order to prevent waste of tobacco, the conveyor is preferably provided with a housing consisting of a floor 20 and upright sides 21.

For maximum efficiency in operation, it is desirable that the tobacco to be treated be uniformly and continuously fed to the chamber, regardless of the manner in which the tobacco is disposed upon the conveyor 14. Accordingly, an adjustable doffer or regulator having fingers 22 is mounted on a shaft 23, rotatably mounted in arms 24 carried by the supports or A frames 19. The doffer is driven by a belt 25 from the shaft 26, by means of the pulley 18.

The conveyor 14, having its upper end extending around the pulley 18, is driven from the pulley 18 by means of its supporting shaft 26. This shaft is provided with a pulley 27 driven by a belt 28 from a pulley 29 on a shaft 30 from a motor 31.

In order to provide a reduced pressure within the chamber 10 and produce an upward movement of air within the chamber and in order to reduce the speed of falling of the leaves into the chamber, as well as to cause the lighter portions of the leaves to be disposed upwardly, suction is applied to the upper end of the chamber by means of an air duct or a conduit 32 connected to a pump 33, air being drawn in at the bottom of the chamber. The pump has a shaft 34 carrying a pulley 35 driven by a belt 36 from a pulley 37 on the motor shaft 30.

To impart intermittent impulses to the leaves in the chamber 10, a butterfly valve 38 on a shaft 39 having a pulley 40, driven by a belt 41 from a pulley 42 on the shaft 26, is employed. The rotation of the shaft will intermittently interrupt the suction through the pipe 32.

A baffle 43 and a screen 44 may be used to prevent the leaves from being sucked from the suction chamber into the pipe 32. Likewise, a control valve 45 may be located in the pipe 32, near the pump 33, if desired for convenience. By means of this control valve 45 the amount of suction in the chamber may be controlled.

It will be readily understood that leaves, such as tobacco leaves, fed to the assorting chamber 10, will flow downwardly gradually, due to the reduction in pressure caused by the pump 33. In order to cause the leaves to be discharged in an orderly manner from the chamber 10, a channel box or chute 46 having parallel guide plates 47 is supported by hinge members 48, bolted or otherwise secured to the lower end of the front wall defining the chamber 10. The plates 47 are preferably maintained in spaced relation at their rear ends by a connecting bar 49, extending across the top of the same, leaving the space between the plates 47 providing ways open from top to bottom at the rear end of the channel box 46. Since the channel box is open at the top and bottom, orientation of the leaves will occur by the leaves falling by gravity from the chamber 10 and settling into the ways or spaces between the parallel walls. In order to cause these leaves to move endwise and be discharged, a horizontal conveyor 50 is mounted beneath the channel box or pulleys 51 and 52 on shafts 53 and 54, the shaft 54 being driven by means of a pulley 55, belt 56 and pulley 57, on shaft 26.

In order to prevent leaves from becoming lodged on the plates 47 of the channel box 46, knobs or projections 58 on the conveyor 50, pref-

erably a row at each side of the conveyor, are provided for contact with each end wall of the channel box, thus the channel box will be oscillated or vibrated on its pivotal mountings due to its rear end being engaged by the projections 58.

Any desired means may be employed for carrying away the leaves discharged by the conveyor 50 from the channel box, for example, a conveyor 59 may be carried on suitable pulleys 60 on shafts 61 and 62 in bearings 63. The shaft 61 may be driven by a belt 64 directly from the motor shaft 30. A bridge 65, suitably mounted, as for example on shaft 53, may be employed between the horizontal conveyors at the lower end of the chamber for preventing the leaves from becoming lodged between the two conveyors.

Instead of the mechanism being driven from a single motor, as illustrated, a plurality of driving 20 motors or other driving means may be employed. Also, conveyors of other character may be employed, although it is quite important that means be employed for providing parallel channels for the leaves.

25 In order that the apparatus may be operated with maximum efficiency, it is necessary to co-ordinate the several elements and operations of the device. For example, it is necessary to correlate the height of the chamber, the amount of suction, the amount of material to be treated, the continuous uniform supply and discharge, and the interruption of the suction to the chamber for best results.

30 The conveyor should move as rapidly as possible to treat the maximum amount of material, but not faster than to satisfactorily handle the material, and there should be sufficient airflow through the chamber to cause the leaves to be properly arranged. Thus, as with any machine, 40 the adjustment of the several operating parts is advisable.

In the operation of the device, tobacco or other leaves are dumped, or otherwise deposited, onto the conveyor 14, and are carried up for introduction into the chamber 10, the doffer serving to thin out, regulate, and produce uniform flow down the chute 13, and through the inlet 11, into the chamber 10. Suction by the pump 33 through the pipe 32 will produce a reduction in the air 50 pressure within the chamber 10, such reduction being intermittently interrupted or given a pulsating effect by means of the butterfly valve 38, so that the leaves will be caused to turn over and float with their stem ends downwardly, until they settle gently through the channel box 46, onto the conveyor 50, for discharge, stems first, lengthwise onto the conveyor 59.

It will be obvious to those skilled in the art that various changes may be made in the invention 60 without departing from the spirit and scope thereof, and therefore the invention is not limited by that which is shown in the drawings and described in the specification, but only as indicated in the appended claims.

What is claimed is:

1. A tobacco leaf arranging machine comprising a relatively tall arranging chamber having a reduced discharge outlet adjacent its lower end for the inlet of air and for the discharge of leaves from said chamber, means for withdrawing air from the upper portion of said chamber, for producing an upward flow of air through said chamber and for decreasing the air pressure in said chamber, means for controlling the amount of withdrawn air, means for feeding leaves into the

upper portion of said chamber so that said leaves may move downwardly under the influence of gravity with such downward movement retarded by the movement of air in said chamber, a baffle in said chamber for preventing leaves fed into the chamber from being subjected to the direct action of the air suction, a screen in said chamber for preventing leaves from being carried out of the upper end of the chamber, a chute beneath the discharge outlet having individual slideways for the leaves discharged, a conveyor adjacent said discharge outlet for receiving the leaves from said chute, and unitary means for driving said air withdrawing means and said conveyor.

2. A tobacco leaf arranging machine comprising an arranging chamber disposed in an upright position and having reduced upper and lower ends, means for drawing air upwardly through said chamber, means for controlling the amount of air drawn through the chamber, means for feeding leaves into the upper portion of the chamber, a baffle in said chamber for preventing leaves fed into the upper end of the chamber from being sucked directly out of the chamber, a screen in said chamber for preventing leaves from being carried out of the upper end of the chamber, a chute adjacent the lower end of said chamber having individual ways for receiving leaves, stem first and causing them to be discharged from said chute in like manner, and a conveyor beneath the lower end of the chute for receiving the leaves and transferring and discharging them at a distance therefrom in an assorted arrangement.

3. A tobacco leaf arranging machine comprising a relatively tall arranging chamber having a reduced discharge outlet adjacent its lower end for the inlet of air and for the discharge of leaves from said chamber, means for producing an upward flow of air through said chamber and for decreasing the air pressure in said chamber, means for feeding leaves into the upper portion of said chamber so that said leaves may move downwardly under the influence of gravity with such downward movement retarded by the movement of air in said chamber, a baffle in said chamber for preventing leaves fed into the chamber from being subjected to the direct action of the air suction, a screen in said chamber for preventing leaves from being carried out of the upper end of the chamber, a chute beneath the discharge outlet having individual slideways for the leaves discharged, a conveyor for receiving the leaves from said chute, and unitary means for driving said air withdrawing means and said conveyor.

4. A leaf arranging device comprising a relatively tall chamber having a discharge outlet adjacent its lower end, means for producing movement of air upwardly in said chamber, means for feeding leaves into said chamber so that they may be subjected to the combination of gravity and air movement and thereby be caused to assume a position with the heavy stem portions of the leaves downwardly, a conveyor disposed adjacent said discharge outlet and means disposed between said discharge outlet and said conveyor for depositing leaves on said conveyor in spaced parallel arrangement.

5. A leaf arranging device comprising a relatively tall chamber having a discharge outlet adjacent its lower end, means for producing movement of air upwardly in said chamber, means for feeding leaves into said chamber so that they may be subjected to the combination of gravity and air movement and thereby be caused to assume a position with the heavy stem portions of the

leaves downward, receiving means for the leaves discharged from said chamber and constructed to cause the leaves to assume a definite assorted arrangement, said receiving means including a chute having individual ways disposed adjacent said discharge outlet and a conveyor beneath the chute transferring and discharging the leaves.

10 6. A leaf arranging device comprising a relatively tall chamber having a discharge outlet adjacent its lower end, means for producing movement of air upwardly in said chamber, means for intermittently interrupting the movement of air during operation of said device, means for feeding leaves into said chamber so that they may be subjected to the combination of gravity and air movement and thereby be caused to assume a position with the heavy stem portions of the leaves downward, a conveyor disposed adjacent said discharge outlet and means disposed between said discharge outlet and said conveyor for depositing leaves on said conveyor in spaced parallel arrangement.

20 7. A leaf arranging device comprising a relatively tall chamber having a discharge outlet adjacent its lower end, means for producing movement of air upwardly in said chamber, means for feeding leaves into said chamber so that they may be subjected to the combination of gravity and air movement and thereby be caused to assume a position with the heavy stem portions of the leaves downward, receiving means for the leaves discharged from said chamber and constructed to cause the leaves to assume a definite assorted arrangement, said receiving means including mechanism defining individual ways disposed adjacent said discharge outlet into which said leaves are adapted to gravitate, and means for shaking said last mentioned means to prevent leaves from becoming lodged thereon.

30 8. A leaf arranging device comprising a relatively narrow chamber having a combination air inlet and discharge outlet adjacent its lower end, means for producing movement of air upwardly in said chamber, an elevating conveyor for feeding leaves to the upper portion of the chamber so that they may be subjected to gravity and air movement contrary to gravity, in said chamber and with the influence of gravity greater than the influence of air movement, means for intermittently interrupting the movement of air in said chamber in timed relation to the operation of said conveyor to provide additional agitation for the leaves, and a bottomless channel box disposed adjacent said discharge outlet to receive the leaves discharged from the discharge outlet of said chamber.

40 9. A leaf arranging device comprising a relatively narrow chamber having a combination air inlet and discharge outlet adjacent its lower end, means for producing movement of air upwardly in said chamber, an elevating conveyor for feeding leaves to the upper portion of said chamber so that they may be subjected to gravity and air movement contrary to gravity, in said chamber and with the influence of gravity greater than the influence of air movement, means for intermittently interrupting the movement of air in said chamber to provide additional agitation for the leaves, a bottomless channel box disposed adjacent said discharge outlet to receive the leaves discharged from the discharge outlet of said chamber, said channel box having parallel partition members for producing orientation of the leaves so that they will be discharged with their stems first in parallel relation, and means for

producing vibration of said channel box to prevent leaves from becoming lodged thereon.

10. A leaf arranging device comprising a relatively narrow chamber having a combination air inlet and discharge outlet adjacent its lower end, means for producing movement of air upwardly in said chamber, an elevating conveyor for feeding leaves to the upper portion of the chamber so that they may be subjected to gravity and air movement contrary to gravity in said chamber and with the influence of gravity greater than the influence of air movement, means for intermittently interrupting the movement of air in said chamber to provide additional agitation for the leaves, a bottomless channel box disposed adjacent said discharge outlet to receive the leaves discharged from the discharge outlet of said chamber, and a conveyor with an upper run disposed adjacent the bottom of said channel box, movable to carry the leaves endwise along and from said channel box.

11. A leaf arranging device comprising a relatively tall and wide chamber having a combination air inlet and discharge outlet adjacent its lower portion, an air duct connected to the upper end of said chamber, a suction pump for producing flow of air in said chamber and through said duct, valve means for controlling and intermittently interrupting said flow of air, an elevating conveyor for feeding leaves into the upper portion of said chamber so that they may be subjected to gravity and air movement contrary to gravity in said chamber, and with the influence of gravity greater than the influence of air movement and with such air movement being subject to intermittent interruption by said valve means to provide additional agitation for the leaves, a bottomless channel box disposed adjacent said discharge outlet to receive the leaves discharged from said discharge outlet, said channel box having partition members for producing orientation of the leaves so that they will be discharged with their stems first in parallel relation, and means for producing vibration of said channel box to prevent the leaves from becoming lodged thereon. 45

12. A leaf arranging device comprising a relatively tall and wide chamber having a combination air inlet and discharge outlet adjacent its lower portion, an air duct connected to the upper end of said chamber, a suction pump for producing flow of air in said chamber and through said duct, valve means for controlling and intermittently interrupting said flow of air, an elevating conveyor for feeding leaves into the upper portion of said chamber so that they may be subjected to gravity and air movement contrary to gravity in said chamber, and with the influence of gravity greater than the influence of air movement and with such air movement being subject to intermittent interruption by said valve means to provide additional agitation for the leaves, a bottomless channel box disposed adjacent said discharge outlet to receive the leaves discharged from said discharge outlet, said channel box having partition members for producing orientation of the leaves so that they will be discharged with their stems first in parallel relation, means for producing vibration of said channel box to prevent the leaves from becoming lodged thereon, and a conveyor with an upper run disposed adjacent the bottom of said channel box, and movable to carry the leaves endwise along and from said channel box.
